THROTTLING MEANS FOR INTERNAL COMBUSTION ENGINES

Louis Brown and Richard J. Jones,
San Antonio, Tex.

Application August 1, 1934, Serial No. 738,692

7 Claims. (Cl. 74—513)

This invention relates to a throttling means for use in controlling the speed of an internal combustion engine.

The invention has for one of its aims the provision of simple means by which the accelerator pedal of an automobile engine may be conveniently and automatically held in a set position without the continued application of foot pressure and in this way, the operator is relieved of a portion of the strain incident to driving, particularly on long runs, in addition to which there is to be considered the reduced wear accompanying a uniform engine speed in contrast to the wear due to fluctuating engine speeds and, of course, a uniform engine speed avoids excessive fuel consumption and flooding the various fuel chambers.

The invention also contemplates a novel governing means by which a constant engine speed may be maintained even though the load upon the engine is varied, due to hill climbing and other reasons, and it will be found that such constant engine speed is maintained without disturbing the previous setting of the accelerator pedal.

With further reference to the governor phase of the invention, it is pointed out that the setting of the governor is determined by the position of the accelerator pedal, with the result that the governor is operative at all engine speeds and requires no separate adjustment aside from ordinary and conventional accelerator pedal actuation to maintain a desired or required engine speed.

Another attribute of the invention resides in the fact that while the invention provides for the maintenance of a constant engine speed when such speed is desired, nevertheless, the accelerator pedal embodied in the invention is operated after the fashion in which a conventional accelerator is operated, providing a highly responsive means by which the speed of the engine may be either increased or decreased to meet the requirements of driving in congested places.

Another object of the invention is to provide a throttling means of the character indicated which may be easily and quickly applied to an engine, either during the course of manufacture or at any time thereafter, without elaborate changes in the design of the engine and without the exercise of unusual skill.

A further object is to provide a structure of the character described which is of highly simplified construction, durable in use and relatively cheap to manufacture.

Other objects and advantages will be apparent during the course of the following description.

In the accompanying drawings, forming a part of this application and in which like numerals are employed to designate like parts throughout the same,

Figure 1 is a fragmentary plan view of the throttling means applied,

Figure 2 is a side elevation of the controlling means applied, parts being shown in section,

Figure 3 is a fragmentary longitudinal sectional view illustrating a governing unit embodied in the invention, the view being taken on line 3—3 of Figure 1,

Figure 4 is a sectional view taken on line 4—4 of Figure 1,

Figure 5 is a sectional view taken on line 5—5 of Figure 3,

Figure 6 is a sectional view taken on line 6—6 of Figure 1.

In the drawings, the numeral 10 designates an accelerator pedal which may, of course, be pivotally mounted in any preferred manner.

In carrying out the invention, the accelerator pedal 10 is pivotally connected to a combination motion transmitting and valve rod 12, such connection being through the intervention of a link 14.

As shown in Figure 2, the combination motion transmitting and valve rod 12 extends longitudinally into a cylinder 16 from one end of the cylinder and has operative connection with a piston 18. More specifically, what might be said to be the inner end of the rod 12 is formed with a spherical head constituting a valve element. Such valve element co-acts with the piston 18 in controlling the fluid within the surrounding chamber. That is to say, the piston 18 is longitudinally ported in the head thereof and the spherical head of the rod 12 is adapted to contact the valve seat at one end of such port.

When the spherical head of the rod 12 is in seated position, the port in the piston is closed. On the other hand, when the spherical head of the rod 12 is unseated, the fluid in the surrounding chamber may pass freely through the piston 18.

The cylinder 16 is rigidly mounted upon a bracket 17 which, in turn, is secured by bolts or the like to a support, such as the floor board of an automobile.

As illustrated in Figure 4, the cylinder 16 is provided intermediate the ends thereof with a partition 22 dividing the cylinder into chambers 24 and 26.

Clearly, it is within the chamber 24 that the valved piston operates and, in addition, a body 55

of liquid, such as oil, is located within the chamber 24 for releasably securing the pedal in a set position.

From further inspection of Figure 4, it will be seen that advancement of the pedal 10 will unseat the spherical head of the rod 12 and thereby allow fluid to pass through the ported head of the piston 18 and thereby permit of advancement of the piston 18. With the unseating of the spherical head of the rod 12, such head is brought into motion transmitting engagement with the inner end wall of a socket 30, the said socket being located in the diametrically enlarged end portion of a piston rod 34. The diametrically enlarged socketed end portion of the piston rod 34 is shown to be provided with spaced ports 40 by which fluid in the surrounding chamber 24 may enter the socket 30 for passage through the ported head of the piston 18.

It is also shown in Figure 4 that a rather light expansion spring 44 is mounted upon the accelerator rod 12 at a point between the piston 18 and a retaining element 48 shouldered upon the rod 12. The spring provides a simple means by which the pedal 10 and the associated rod 12 are urged to the retracted positions shown in Figure 2 to normally inhibit the passage of fluid through the ported piston 18.

Thus, when the accelerator pedal has been advanced to the desired position and foot pressure thereon is released, the spherical head of the rod 12 will resume its seated position and prevent the passage of fluid through the ported piston. In this way, the piston 18 is held against axial movement until intentionally shifted.

At this point, it might be noted that while the piston 18 and associated parts provide a means for holding the pedal against movement so long as no foot pressure remains on the pedal, the application of slight foot pressure to the accelerator pedal will hold the spherical head of the rod 12 in an unseated position to permit the flow of fluid through the piston 18. This allows the piston and associated parts to be retracted under the influence of the springs 50 as will be hereafter more fully described.

From the foregoing, it will be seen that substantial or material depression of the pedal 10 results in advancement of the piston 18 and associated parts for the obvious purpose of increasing the speed of the engine. On the other hand, when it is desired to produce a reduced speed setting, a light pressure will be exerted on the accelerator pedal sufficient to move the spherical head of the element 12 from its seat in the piston 18 and permit the flow of oil therethrough, but insufficient to move such spherical head into engagement with the adjacent end of the piston rod 34. By this arrangement, the piston 18 may move backward under the influence of the springs 50 and the fluid in what might be said to be the rear portion of the chamber 24 is passed through the port in the piston 18. Thus, a light foot pressure on the accelerator pedal provides for a new engine setting looking to a reduced engine speed. When the speed of the engine has been re-set at a reduced number of revolutions per minute, the accelerator pedal is abruptly released so as to allow the spherical head of the member 12 to close the port in the head 18, whereupon the fluid in the chamber 24 is prevented from passing through the piston. This, of course, holds the piston 18 against movement in either direction with the result that the speed of the engine is maintained at this point until increased

or decreased. This provides the delicate speed control necessary for use in traffic. In this connection, it is observed that the pedal itself handles in a fashion not unlike that in which the ordinary accelerator pedal is operated.

For operation of the engine at a predetermined speed, the accelerator pedal is advanced to the required position and is abruptly released to close the ported or valved piston 18 and thus secure the piston in its newly set position where it 10 remains until changed.

Also, depression of the brake pedal 60 results in release of the piston 18 so that such piston and the pedal 10 may return to retracted position. In explaining this, attention is directed to Figure 4 in which it is illustrated that there is a by-pass 70 of U-shaped form in which the ends or branches thereof are in constant communication with the chamber 24 at opposite sides of the piston 18. A valve 72 of any preferred design is located in the by-pass 70 and is provided with an operating arm 74 having a longitudinal slot 76 slidably receiving a laterally projecting pin 78 carried by the foot pedal.

From Figure 2, it is clear that depression of the 25 brake pedal 60 rocks the arm 74 and thereby turns the valve 72 to open position. Such movement of the valve 72 allows the flow of previously trapped fluid through the by-pass 70, so that the piston 18 may be retracted under the influence of 30 the springs 50. Obviously, the flow of fluid through the by-pass 70 will be from the pedal end of the chamber 24 into what might be said to be the forward end of this chamber.

By referring to Figure 2, it will be seen that the 35 rod 34 is provided with a piston head 80 operating within the chamber 26 within which there is a body of liquid, such as oil, or some other relatively non-compressible fluid. More specifically, a body of liquid is confined between the piston 80 40 and a second piston 84 of a substantially smaller cross-sectional area. The piston 84 operates in a part of the chamber 26 of a reduced cross-sectional area.

By reason of the difference in the areas of the 45 pistons 80 and 84 and the bores within which these parts operate, advancement of the piston 80 will result in greater advancement of the piston 84.

By this arrangement, a slight depression of the 50 foot pedal will result in a somewhat greater movement on the part of the carburetor controlling means. This provides great responsiveness to slight changes in the position of the accelerator pedal.

It is illustrated in Figure 2 that the piston 84 has connection with a governing unit generally designated by the numeral 90, such governing unit embodying a cylinder 92 enclosing a hollow piston 96 and a spring 94 of a predetermined 60 power. More specifically, the spring 94 is confined between the piston 96 and an adjusting head 98. The head 98 is carried by a shank 100 threaded through one end of the cylinder 92 and having pivotal connection with the piston 84. 65

The piston 96 is shown to have a connecting rod 103 pivotally connected with the arm 104 of the fuel inlet butterfly valve through the intervention of a pivot element 106. A wing nut 107 or the like is associated with the pivot element 70 106 to maintain a predetermined relation or adjustment between the rod 103 and the arm 104.

Incidentally, the threaded connection between the rod 100 and the cylinder 92 provides a simple means by which the spring 94 may be moved 75

endwise and bodily in the cylinder 92 for the purpose of locating the arm 104 in its idling position when the accelerator pedal is fully retracted. In other words, the threaded connection between the parts 92 and 108 provides a means by which the over-all length of the governing unit may be varied so that when the accelerator pedal is in fully retracted position, the arm 104 will be in the motor idling position.

Now, by way of more specific reference to the structure and operation of the governing unit, it is pointed out that when the engine is at an idling speed, the spring 94 is not loaded and that depression of the accelerator pedal will result in the advancement of the cylinder 92 to load the spring 94 and thus bring about opening of the butterfly valve in the intake manifold. However, concurrently with the opening of the butterfly valve, there will be created a partial vacuum in the air intake port of the carburetor and such partial vacuum is caused to act within the cylinder 92 to retard the advancement of the piston 96. The vacuum thus created within the cylinder 92 will be found to act in opposition to the expansive force of the spring 94. It will, therefore, prevent the piston from having a forward movement co-extensive with that of the cylinder 92.

Thus, when the foot pedal 10 is advanced, the vacuum within the cylinder 92 will be increased to a point where it approximately balances the power of the spring 94 so as to secure the piston 96 in a predetermined position so long as the load on the motor remains constant. However, should the load on the motor increase, there will be a reduction in the partial vacuum operating within the cylinder 92. Hence, the power of the spring 94 will then be superior to the vacuum prevailing within the cylinder 92 with the result that the piston 96 is advanced to bring about a further opening of the butterfly valve. By reason of this, an increased load will result in an increased fuel supply so as to maintain the desired uniform speed.

When the increased load has been taken care of by a temporarily augmented fuel supply, the vacuum within the cylinder 92 is increased to a point where the spring 94 is overpowered for a period sufficient to return the piston 96 to the position required for the maintenance of a constant speed.

It is important to observe that the vacuum conducting tube 110 connected to the cylinder 90 is not attached directly to the intake manifold at a point between the butterfly valve and the combustion chambers as in the case of other governors, but, on the contrary, such tube is connected to the air intake nipple or end 120 of the carburetor.

More specifically, the air intake nipple of the carburetor is provided with a cone-shaped element 140 having a central conical air passage of a minimum area substantially less than that of the nipple 120, with the result that the velocity of air at this point is greatly accelerated. It will be seen that the tube 110 is connected to the nipple 120 immediately adjacent to the diametrically restricted end portion of the element 140, and it is at this point that the vacuum has been found to be proportional to the speed of the engine. That is to say, when the speed of the engine is low, a low vacuum prevails at this point. On the other hand, as the speed of the engine increases, the vacuum within the inlet member 120 is correspondingly increased.

In operation, the pedal 10 is advanced to the required position and is temporarily locked by the fluid within the cylinder 16 and the governing unit will provide for the automatic maintenance of a required engine speed without alteration 5 in the position of the accelerator pedal.

As shown in Figure 3, the contractile coil springs 80 are secured at their forward ends to the cylinder 92 and the rear ends thereof to the fixed cylinder 16 and provide a means by which 10 the governing unit 90 is urged rearward to retract the piston 96 and the parts actuated thereby.

From an inspection of Figure 2, it will be seen that the arm 104 is longitudinally slotted for the adjustable accommodation of the pivot element 15 106. This provides a simple means by which the parts may be adjusted to give a greater or less swing or movement to the arm 104 in response to a predetermined movement of the piston 96. In this way, the vacuum prevailing within the 20 cylinder 92 is allowed to cooperate with the spring 94 to the best advantage in exercising delicate control over engine speed.

The invention may be applied to aeroplane engines to maintain a constant speed under varying loads and may also be applied to tractors and stationary engines.

Having thus described the invention, what is claimed is:

1. In a speed control mechanism for internal 30 combustion engines, a cylinder for the reception of a relatively non-compressible fluid, a piston in the cylinder and having a port, a combination motion transmitting and valve rod extending through said port and having a head for engaging the forward end of the port so that advancement of the combination motion transmitting and valve rod unseats the head and uncovers the port for the passage of fluid, and spring means urging the head into port closing 35 position.

2. In a speed control mechanism for internal 45 combustion engines, a cylinder for the reception of a relatively non-compressible fluid, a piston in the cylinder and having a port, a combination motion transmitting and valve rod extending through said port and having a head for engaging the forward end of the port so that advancement of the combination motion transmitting and valve rod unseats the head and uncovers the port 50 for the passage of fluid, spring means urging the head into port closing position, and a pedal having operative connection with said rod.

3. In a speed control mechanism for internal 55 combustion engines, a cylinder for the reception of a relatively non-compressible fluid, a piston in the cylinder and having a port, a combination motion transmitting and valve rod extending through said port and having a head for closing the port, spring means urging the head into 60 port closing position, a pedal having operative connection with said rod, and a by-pass connected to said cylinder at opposite ends of said piston.

4. In a speed control mechanism for internal 65 combustion engines, a cylinder for the reception of a relatively non-compressible fluid, a piston in the cylinder and having a port, a combination motion transmitting and valve rod extending through said port and having a head for closing the port, spring means urging the head into port 70 closing position, a by-pass connected to said cylinder at opposite ends of said piston, a valve controlling said by-pass, and a pedal controlling said valve.

5. In a speed control mechanism for internal 75

combustion engines, a cylinder for the reception of a relatively non-compressible fluid, a piston in the cylinder and having a port, a combination motion transmitting and valve rod extending through said port and having a head for closing the port, spring means urging the head into port closing position, a pedal having operative connection with said rod, and a pair of cooperating motion transmitting spaced pistons in responsive relation to said first-named piston.

6. In a speed control mechanism for internal combustion engines, a cylinder for the reception of a relatively non-compressible fluid, a piston in the cylinder and having a port, a combination motion transmitting and valve rod extending through said port and having a head for closing the port, spring means urging the head into port

closing position, a pedal having operative connection with said rod, and a motion transmitting unit actuated by said piston.

7. In a mechanism for controlling the speed of an internal combustion engine, a cylinder for the reception of a fluid, a piston in the cylinder and having a port, a combination motion transmitting and valve rod having a head for closing said port, and a motion transmitting element having a socketed portion rigidly connected to said piston and receiving said head and having a portion in position for engagement by said head to transmit motion from said rod to said element.
